MULTIPLE KEYBOARD UNIT

Percy Dean Olson, Owatonna, Minn., assignor to
Musitronic Inc., Owatonna, Minn.

Filed Dec. 14, 1970, Ser. No. 26,453

Term of patent 14 years

U.S. Cl. D56—9   Int. Cl. D17—01

FIG. 1

FIG. 2

FIG. 3

FIG. 4

FIG. 1 is a top plan view of a multiple keyboard unit, showing my new design;

FIG. 2 is a side elevational view, the opposite side being substantially a mirror image thereof;

FIG. 3 is an end elevational view looking at the right end in FIG. 1; and

FIG. 4 is a left end elevational view, looking at the left end in FIG. 1.

I claim:

The ornamental design for a multiple keyboard unit, substantially as shown and described.
